US0D1052507S

(12) **United States Design Patent** (10) Patent No.: **US D1,052,507 S**
(45) Date of Patent: ** Nov. 26, 2024

(54) **VEHICLE WHEEL RIM**

(71) Applicant: **Mercedes-Benz Group AG**, Stuttgart (DE)

(72) Inventors: **Bernhard Hans**, Stuttgart (DE); **Kai Hilpert**, Stuttgart (DE)

(**) Term: **15 Years**

(21) Appl. No.: **35/518,396**

(22) Filed: **Sep. 19, 2022**

(80) **Hague Agreement Data**

Int. Filing Date: **Sep. 19, 2022**

Int. Reg. No.: **DM/224196**

Int. Reg. Date: **Sep. 19, 2022**

Int. Reg. Pub. Date: **Sep. 22, 2023**
